DESIGN FOR A HAT

Jack E. Newman, New York, N. Y.

Application November 22, 1939, Serial No. 88,420

Term of patent 3½ years

To all whom it may concern:

Be it known that I, Jack E. Newman, a citizen of the United States, residing at New York, in the county of New York and State of New York, have invented a new, original, and ornamental Design for Hats, of which the following is a specification, reference being had to the accompanying drawing, forming part thereof.

I claim:

The ornamental design for a hat, as shown.

JACK E. NEWMAN.
